CLAIM

The ornamental design for a powered air purifying respirator unit control panel, as shown and described.

DESCRIPTION

FIG. 1 is a perspective view showing the new design for a powered air purifying respirator unit control panel;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken line showing of the powered air purifying respirator unit illustrates the environment of the claimed design and forms no part thereof.
